UNITED STATES PATENT OFFICE.

HOMER A. STREIT, OF ROCK FALLS, ILLINOIS.

GAME DEVICE.

Application filed February 24, 1925. Serial No. 11,207.

To all whom it may concern:

Be it known that I, HOMER A. STREIT, a citizen of the United States, residing at 804 Leroy Avenue, Rock Falls, in the county of Whiteside and State of Illinois, have invented a new and useful Improvement in Game Devices, of which the following is a specification.

My invention relates to that type of game devices which comprise, generally stated, a board portion equipped at one end with a device adapted to be operated by the one playing the game, for projecting an object, as for example, a ring, miniature horseshoe, or other suitable object toward the opposite end of the board and relative to an element, or mark, at this end of the board, as for example an upstanding pin or pocket.

My object, generally stated, is to provide a novel, simple and inexpensive construction of game device of the general type referred to.

Certain of my objects, specifically stated, are to provide an improved construction of projecting, or pitching, device, which may be manufactured economically and will operate effectually; to provide for the lengthening and shortening of the board portion of the device, as desired; and to provide a combined ringing-pin and support at one end of the board.

Referring to the accompanying drawings, wherein my invention is illustrated as embodied in a device for pitching a miniature horseshoe toward a peg:

Figure 1 is a plan view of the game device showing a horseshoe in position to be operated by the pitcher or projector device, and by dotted lines ringing the pin. Figure 2 is an edge view of the structure shown in Fig. 1. Figure 3 is a bottom view of that portion of the device which is equipped with the projector. Figure 4 is an enlarged section taken at the line 4—4 on Fig. 1 and viewed in the direction of the arrows, this view showing the projector in the position it assumes when swung upwardly to its extreme position; and Figure 5, a section taken at the line 5—5 on Fig. 4 and viewed in the direction of the arrows.

The game device comprises a board portion, which may be constructed of any suitable material, as for example, and as shown of sheet metal, this board portion being formed of two telescoping sections 6 and 7, which are adjustable lengthwise of each

other. Each of the sections 6 and 7, the section 6 being slightly narrower than the section 7, is provided at its opposite edges with downwardly and inwardly inclined flanges, 60 these flanges being represented at 8 and 9, respectively, and telescoped with each other, as shown in the assembled condition of the sections.

The section 6 is shown as provided, adjacent its extreme outer end, with blocks 10, forming legs, upon which the board is supported at one end in spaced relation to a support, as for example a table upon which it may be set. The opposite end of the 70 board is shown as supported through the medium of a combined ringing-pin and supporting member 11 which is shown as in the form of a peg having a headed portion 12 at its lower end. The peg 11 extends at its portion of lesser diameter, upwardly through an opening 13 in the section 7 adjacent its outer end, its upwardly extending portion forming the pin toward which the object is thrown or projected, by the projector, and its depending portion presenting a supporting leg for the board.

The projector, or pitcher, hereinbefore referred to, comprises, in accordance with the preferred embodiment of my invention, a plate portion 14 connected, by a neck portion 15, with a plate portion 16 extending substantially at a right angle to the portion 14, and terminating in a plate portion 17 extending generally parallel with the plate portion 14 but in the opposite direction from the plate portion 16, and a cross bar 18 rigidly connected to the plate portion 17, as by rivets 19 and provided at its opposite ends with upwardly offset portions 20.

The projector device described is assembled with the board portion of the device to a position in which it extends at its neck portion 15 in a slot 21 located in the board section 6 and extending crosswise thereof, the plate portion 14 being located above the board portion and in its horizontal position extending rearwardly as shown in Figs. 1, 2 and 3, the remainder of the projector device extending beneath the board section carrying it, with the bar portion 18 disposed in front of the slot 21 in the normal position of the projector device, as shown in the figures referred to, the bar member 18 being of such length that it projects laterally at both ends, beyond the opposite edges of the board section 6, as shown, the flanges 8 being

cut away, as represented at 22, to prevent interference with the operation of the projector.

The portions 14, 15, 16 and 17 of the projector, are preferably formed from a single sheet of metal, in which case, and in order to permit of the assembly of the projector with the board, the metal of the section 6 is slit outwardly from the ends of the slot 21 along the angularly disposed lines 23 and 24, thereby forming a tongue 25 which may be bent out of the plane of the board section 6 to present an opening through which the plate portion 14 may be inserted to the position shown in Figs. 1, 2 and 3, whereupon this tongue is then bent back into the plane of the board section 6, to prevent displacement of the projector, while permitting it to be rocked at its neck portion 15, on the section 6 as a fulcrum.

The portions of the projector are so proportioned, as shown that the projector device, at the portion thereof extending above the board, is heavier than the portion thereof of extending below the board, so that the normal position of the projector is that shown in Figs. 1, 2 and 3.

In the use of the device, the object, such as the miniature horseshoe represented at 26, to be thrown toward the peg 11, is positioned on the plate portion 14 as shown in Figs. 1 and 2, and is thrown thereby by the operator striking downwardly against either of the protruding ends 20 of the bar 18, which throws the plate number 14 upwardly and forwardly, carrying with it the object 26, it being understood that the projector automatically returns to normal position (Figs. 1, 2 and 3) after its operation, as above stated.

It will be understood from the foregoing that a projector device constructed in accordance with my invention is not only of simple and inexpensive construction, but is adapted to operate effectually, and is not liable to become out of order.

The feature of providing the adjustment of the board sections 6 and 7 lengthwise of the device, is of advantage in that it permits the user to vary the conditions of play.

While I have illustrated and described a particular construction embodying my invention, I do not wish to be understood as intending to limit it thereto, as the same may be variously modified and altered without departing from the spirit of the invention.

What I claim as new, and desire to secure by Letters Patent, is:

1. A device of the character set forth comprising a board-portion and a pitcher-device, said board portion containing a slot and said device extending into said slot and fulcrumed on an edge thereof to rock.

2. A device of the character set forth,

comprising a board-portion and a pitcher-device, said board-portion containing a slot and said device extending into said slot and fulcrumed between its ends therein, that portion of said device which extends beneath said board-portion extending laterally beyond said board portion for the purpose set forth.

3. A device of the character set forth, comprising a board-portion and a pitcher-device, said board portion containing a slot and said device extending into said slot and fulcrumed between its ends therein, that portion of said device which extends beneath said board-portion extending laterally beyond said board portion at opposite sides thereof, for the purpose set forth.

4. A device of the character set forth, comprising a board-portion containing a slot and a pitcher-device extending through said slot and fulcrumed on an edge thereof, said device presenting a portion, above said board, for engaging the object to be projected, and an actuating portion below said board.

5. A device of the character set forth, comprising a board-portion containing a slot and a pitcher-device extending through said slot and fulcrumed therein, said device presenting a portion, above said board, for engaging the object to be projected, and an actuating portion located below said board, said portions extending in opposite directions from said slot lengthwise of said board-portion.

6. A device of the character set forth, comprising a board-portion containing a slot and a pitcher-device extending through said slot and fulcrumed therein, said device presenting a portion, above said board, for engaging the object to be projected, and an actuating portion located below said board and extending beyond the edge of the latter.

7. A device of the character set forth, comprising a board-portion containing a slot and a pitcher-device of general Z shape extending at its intermediate portion in said slot and at its end portions above and below said board portion.

8. A device of the character set forth, comprising a board-portion containing a slot and a pitcher device of general Z-shape extending at its intermediate portion in said slot and at its end portions above and below said board-portion with the portion thereof below said board-portion presenting a bar portion extending laterally beyond a side of said board-portion.

9. In a game-device, the combination of a board-portion containing an opening therethrough near one end, a combined board-supporting and a game-pin member located in said opening, said member projecting upwardly and downwardly from said board portion, supporting means for the board ad-

- 11 jacent its other end and a projector on said board-portion comprising an operating element movable below said board-portion.
10. In a game-device, the combination of a board-portion containing an opening therethrough near one end, a combined board-supporting and a game-pin member located in said opening, said member having its upper end of reduced cross-section at which portion it extends upwardly through said opening, supporting means for the board adjacent its other end and a projector on said board-portion comprising an operating element movable below said board portion.
11. In a game device, the combination of a board portion formed of sections relatively adjustable lengthwise thereof, and a projector on one of said sections for the purpose set forth.
12. A device of the character set forth, comprising a board containing a slot and a pitcher-device, having a neck-portion at which it extends into, and is fulcrumed in, said slot.

13. A device of the character set forth, comprising a board containing a slot and a pitcher-device, having a neck-portion at which it extends into, and is fulcrumed in, said slot, said slot being of less length than the width of the portions connected by said neck, with slits in said board extending from the ends of said slot and forming a deflectable tongue of a width greater than the length of said slot.

14. A device of the character set forth, comprising a board containing a slot and a pitcher-device, having a neck-portion at which it extends into, and is fulcrumed in, said slot, said slot being of less length than the width of the portions connected by said neck, said board being slit to provide a deflectable portion which when deflected presents an opening communicating with said slot and through which an end of said pitcher-device may be introduced to position said neck portion in said slot.

HOMER A. STREIT.
